UNITED STATES PATENT OFFICE.

ADOLPH G. KUPETZ, OF NEW ROCHELLE, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed January 16, 1924. Serial No. 686,475.

This invention relates to means for causing the paper-carriage or other letter-feed carriage of a typewriter to skip automatically between predetermined neighboring points in the carriage-travel.

This method of operation is desired, for example, in typing telephone bills, in which operation it is necessary to type successively in separate columns the company's charge, the United States tax, and a code symbol. In writing these bills it is desired to cause the carriage automatically to jump forward two extra letter-spaces to the tax column at the typing of the last digit in the company's charge column, and then again automatically to jump forward two extra letter-spaces to the code column following the actuation in the tax column of a single tax writing key.

An important object of the invention is to provide means for accomplishing this kind of a result, which can be manufactured cheaply and which can be incorporated in standard typewriting machines at small expense and without substantial alterations of the machine. This is important for two reasons, first it is obviously desirable in the interest of economy of manufacture that the attachments for securing the automatic space-skipping shall be simple and cheap, and shall involve little labor expense; and, second, the special utility of the machines equipped with the invention for writing telephone bills may be terminated by a change in the present tax laws. Should such a change occur it would be desirable to convert the machines to standard construction without having to discard a multiplicity of expensive parts and without extensively altering the machines.

It is further important object of the invention to provide means for effecting automatic tabulating of the kind referred to which will be unfailingly accurate in operation and which will not result in damage to the rack or excessive wear thereof.

All of these results are accomplished in accordance with the present invention by the provision of a single integral device arranged to be fitted on the escapement rack and to be held in place thereon by a single screw. This device includes a vertical web or wall having a screw-hole centrally located therein, and at the opposite ends of its lower extremity a pair of rack-lifting cam projec-

tions arranged to act upon the rack-supporting roller that forms part of the usual tabulating mechanism of the Underwood typewriter, automatically to lift the escapement rack out of engagement with the escapement pinion at predetermined points in the travel of the carriage. The cam projections have horizontal upper faces which snugly engage the roller-engaging lower face of the rack to co-operate with the attaching screw to locate the device accurately and fix it immovably upon the rack.

The first cam of the device to engage the rack-supporting roller in the letter-feeding movement of the carriage lifts the rack out of engagement with the escapement pinion and maintains it out of engagement with the pinion until a jump of two extra letter-spaces has been effected, whereupon the rack and pinion are re-engaged. The second cam is at such a distance from the first cam, however, that it becomes effective at the next letter-feeding movement of the carriage to cause a second jump of two extra letter-spaces.

The cams and roller are arranged to return the rack to engagement with the pinion gradually, and the pinion is controlled by the escapement mechanism to yield when first re-engaged by the rack and to move with the rack until such re-engagement is complete and the normal relation between the pinion and rack has been re-established. This obviates the likelihood of a rack-tooth, in rapid motion, striking the end of a fixed pinion-tooth with which it is intended to mesh and bouncing on to some other position. This is of the utmost importance both because the speedy operation of the machine depends upon the unfailing accuracy of the automatic space-skipping mechanism, and because the violent engagement of the ends of the teeth results in distortion and excessive wear of the teeth.

The cams are also constructed to present beveled faces in engagement with the rack-supporting roller in the anti-letter-feed movement of the carriage to permit the cams to pass the roller without the interposition of yielding cam-supporting means.

It will be seen that the desired automatic space-skipping of the carriage is thus caused to be effected by the rigid attachment of a single unitary device to the escapement rack of a standard Underwood typewriter, and

that such rigid attachment of the device is effected by a single screw. It is a further point that the only alteration of the standard parts of the machine consists in the drilling of a screw-hole in the rack which can be inexpensively made and which would not be objectionable in case it should become desirable to discard the space-skipping attachment.

10 It will be apparent, of course, that devices could be constructed for effecting space-skipping arrangements different from the particular one referred to above without departing from the invention, and that that arrangement should therefore be regarded simply as illustrative of the invention and not in a limiting sense.

Other features and advantages will hereinafter appear.

20 In the accompanying drawings,

Figure 1 is a sectional side elevation of a part of an Underwood typewriter embodying the present invention;

25 Figure 2 is a fragmentary front elevation of the parts of the machine having to do directly with the rack-lifting attachment;

Figure 3 is a perspective view of the attachment;

30 Figure 4 is a fragmentary front elevation, showing the rack in the position occupied just prior to its disengagement from the pinion by the first cam projection;

35 Figure 5 is a view similar to Figure 4, but showing the rack disengaged from the pinion;

40 Figure 6 is a view similar to Figure 5, showing the pinion and rack partially re-engaged, the rack, however, being still held in an elevated position by the engagement of the first cam-extension with the rack-supporting roller; and

45 Figure 7 is a view similar to Figure 6, but showing the rack and pinion fully re-engaged, following the jump effected by the first cam-projection.

In the typewriting machine, types 10 are carried by type-bars 11 actuated by keys (not shown) to swing upwardly and rearwardly against the front face of a cylindrical platen 12 journaled by means of its axle 13 in the ends of a platen-frame 14 mounted in a traveling carriage 15. The carriage travels in letter-feed and return direction along a front rail (not shown) and a rear rail 16, which rails are mounted on the machine-frame 17. The carriage 15 is moved in letter-feed direction by the usual spring-drum 18 to which it is connected by a strap 19. Movement of the carriage 15 under the urging of the spring-drum 18 is controlled by suitable escapement mechanism comprising a rack 20 carried by a swing-frame 21 on the carriage 15 to travel with the carriage, which rack 20 meshes with a pinion 22 having a one-way driving connection through

a pawl 23 with an escapement-wheel 24 that is controlled in turn by fast and loose dogs 25 and 26, respectively, operated by a universal bar 27 in the paths of the type-bars 11.

70 The machine includes the usual tabulating mechanism, which may be like that disclosed in the patent to H. Crutchley, No. 929,080, granted July 27, 1909. This mechanism includes a lever 28 pivoted at 29 that bears 75 a roller 30 at its forward end upon which the rack 20 rests. Means is provided for rocking the lever 28 to raise the roller 30 and thereby lift the rack 20 out of engagement with the escapement pinion 22, when 80 desired. An adjusting screw 31 carried by the lever 28 may be turned to adjust the limit of downward movement of the roller 30 and so to adjust the normal relation of the roller 30 and the rack 20 to the escapement 85 pinion 22. The mechanism thus far described is of the standard Underwood construction.

For the purpose of causing the carriage 15 to jump forward automatically at selected points in its letter-feeding travel, there is provided, in accordance with the present invention, a cam device 32 to be attached to the escapement rack 20. This device comprises a vertical web or wall 33 having a screw-hole 34 centrally located to receive a screw 35 by which it is attached to the rack 20. The device includes cam projections 36 and 37, which extend rearward from the vertical wall 33 and have horizontal upper faces 38 to snugly engage the roller-engaging lower surface 39 of the rack 20. These cam projections 36 and 37 co-operate with the attaching screw 35 to fix the cam device 32 accurately and securely in place upon the rack 20. They also serve to engage the roller 30 at predetermined points in the travel of the rack 20 to lift the rack automatically out of engagement with the escapement pinion 22 and to maintain it thus disengaged from the pinion until a jump of the desired extent has been effected. The parts are shown in Figure 4 as ready for the typing of the last digit in the company's 100 charge column of a telephone bill. It will be observed that a tooth *x* of the rack is in engagement with a tooth *y* of the escapement pinion at this stage. As a result of the next type-stroke the escapement wheel 24 105 moves forward one tooth-space, as usual, but the concurrent advance of the rack 20 thus permitted causes an inclined face 40 of the cam projection 36 to ride up on the roller 30, as seen in Figure 5, to disengage the rack 20 from the pinion 22. The carriage 15, being now unrestrained by the escapement mechanism, continues to move forward until, as shown in Figure 6, the cam 36 has reached a point on the roller 30 which is low enough 110 to permit the rack 20 to again engage the

115 pinion 22. The carriage 15, being now unrestrained by the escapement mechanism, continues to move forward until, as shown in Figure 6, the cam 36 has reached a point on the roller 30 which is low enough 120 to permit the rack 20 to again engage the pinion 22. The carriage 15, being now unrestrained by the escapement mechanism, continues to move forward until, as shown in Figure 6, the cam 36 has reached a point on the roller 30 which is low enough 125 to permit the rack 20 to again engage the pinion 22. The carriage 15, being now unrestrained by the escapement mechanism, continues to move forward until, as shown in Figure 6, the cam 36 has reached a point on the roller 30 which is low enough 130 to permit the rack 20 to again engage the pinion 22.

pinion 22. At this point, the tooth y of the pinion is engaged by a rack-tooth z , which is the second tooth from the rack-tooth x that engaged the pinion-tooth y prior to the jump. 5 From the position of Figure 6 to that of Figure 7 the pinion 22 yields before the rack 20, while the rack is gradually lowered, due to the contours of the cam 36 and the roller 30, so that finally in the position of Figure 10 7 the rack is arrested by the pinion with the rack and pinion-teeth again in their normal fully-engaged relationship.

The arrangement of the escapement-controlling mechanism to permit this yielding 15 of the pinion during the re-engagement of the rack 20 and pinion 22 requires some explanation. When the rack 20 is in the position shown in Figure 4 and a type is 20 swung upward for printing the last digit in the company's charge column, the loose dog 26 is rocked out of engagement with the escapement-wheel tooth 41 and is drawn toward the left, as viewed in Figure 5, by a spring 43, while the fixed dog 25 is rocked 25 into engagement with the tooth 41 to prevent rotation of the escapement wheel 24. On the return stroke of the type, the fixed dog 25 is rocked out of engagement with the tooth 41 and the loose dog 26 is rocked into 30 the path of the next escapement-wheel tooth 42. The escapement wheel 24 is now free to advance a tooth-space, and, as the rack 20 is in mesh with the pinion 22 and is urged in letter-feed direction by the spring-drum 35 18, the carriage 15 advances, causing the rack to rotate the escapement wheel 24, and the escapement-wheel at the same time moves the loose dog 26 toward its initial position against the tension of the spring 43. In the 40 course of this advance of the carriage 15, the rack 20 is lifted out of engagement with the pinion 22, as has been previously explained. As soon as the pinion 22 and the escapement wheel 24 are thus left free of the 45 rack 20, the spring 43, acting through the loose dog 26, backs up the escapement wheel and pinion to the position shown in Figure 5, the wheel 24 being limited in that position by engagement of a back-stop pawl 44 with 50 an escapement-wheel tooth 45. The cam 36 and the roller 30 are so constructed and arranged that the rack 20 is caused to drop gradually into position to cause the rack-tooth z to engage the pinion-tooth y , in the 55 position of the latter tooth shown in Figures 5 and 6, and to continue to drop gradually as the rack and pinion-teeth advance together from the position of Figure 6 to that of Figure 7. By the described arrangement 60 of the escapement mechanism and the rack-lifting mechanism, the rack-lowering period is prolonged, so that ample time is allowed for the rack 20 to descend completely into mesh with the pinion 22 before it is arrested by the pinion. This arrangement is of very

great importance, since it assures the proper re-engagement of the pinion and rack after a jump of the exact extent desired. It is also important for the reason that there is no tendency for the rack or pinion-teeth to 70 be worn away or to get knocked out of shape at their outer ends.

The second cam 37 is constructed like the first, to cause a jump of the same extent in the same manner. The second cam 37 is 75 spaced from the first at such a distance that the rack 20 is caused to engage the pinion 22 for one letter-space only, between the two automatic jumps. When the parts are in the position shown in Figure 7, therefore, the 80 carriage 15 is ready to be automatically released at the next type-stroke by the co-operation of the roller 30 with the inclined face 46 of the second cam 37, to cause the second automatic jump.

Each of the cams 36 and 37 has a beveled lower right-hand face 47 to engage the roller 30 in the return movement of the carriage to facilitate the movement of the device 32 and the roller past each other without the 90 necessity for yieldingly supporting the device or the individual cams.

It will be noted that the roller 30 is key-actuated at one operation, to raise the feed-rack out of engagement with the holding 95 pinion for an extended free movement of the carriage to a column-stop position, and at another operation the roller in its normal position serves as a stationary camming element to automatically disengage the rack 100 and pinion for a very short interval and immediately re-establish engagement thereof. The roller in one instance becomes a movable rack-lifting element and at another interval becomes a stationary rack-lifting 105 element.

Variations may be resorted to within the scope of the invention, and portions of the improvements may be used without others.

Having thus described my invention, I 110 claim:

1. In a typewriting machine, the combination with a traveling carriage, escapement mechanism controlling the letter-feeding of the carriage, comprising an escapement rack 115 on the carriage and a pinion co-operating therewith, and a rack-supporting and lifting roller for disengaging the rack from the pinion to cause a jump of the carriage; of a device attached to the escapement rack 120 to release the carriage automatically from the control of the escapement mechanism at a plurality of predetermined points in the travel of the carriage by moving the rack away from the escapement pinion, consisting of a vertical web having a screw-hole centrally located for receiving a screw to attach it to the rack, and a plurality of projections extending rearward from the vertical web, said projections having horizontal 125 130

- upper surfaces to snugly engage the roller-engaging, lower face of the rack and co-operate with the attaching screw to fix the device securely and accurately in place on the 5 rack, each of the projections having a lower left-hand beveled face to engage the rack-lifting roller and thereby cam the rack away from the escapement pinion in the letter-feed movement of the carriage, and a 10 lower right-hand beveled face to engage the rack-lifting roller to facilitate movement of the projection past the roller in anti-letter-feed direction, each of the projections being constructed to cooperate with the roller 15 to cause a carriage-jump of two extra letter-spaces and the projections being spaced from each other to permit the rack to re-engage the pinion for a single type-stroke between the automatic jumps.
- 20 2. In a typewriting machine, the combination with a traveling carriage, escapement mechanism controlling the letter-feeding of the carriage, comprising an escapement rack on the carriage and a pinion co-operating therewith, and a rack-supporting and lifting roller; of a device attached to the escapement rack to release the carriage automatically from the control of the escapement mechanism at a plurality of predetermined points 25 in the travel of the carriage by moving the rack away from the escapement pinion, consisting of a vertical web having a screw-hole centrally located for receiving a screw to attach it to the rack, and a plurality of projections 30 extending rearward from the vertical web, said projections having horizontal upper surfaces to snugly engage the roller-engaging, lower face of the rack and co-operate with the attaching screw to fix the device securely and accurately in place on the rack, each of the projections having a lower left-hand beveled face to engage the rack-lifting roller and thereby cam the rack away from the escapement pinion in the letter-feed movement 35 of the carriage, and a lower right-hand beveled face to engage the rack-lifting roller to facilitate movement of the projection past the roller in anti-letter-feed direction.
3. In a typewriting machine, the combination with a traveling carriage, escapement mechanism controlling the letter-feeding of the carriage, comprising an escapement rack on the carriage and a pinion co-operating therewith, and a rack-supporting and lifting roller; of a device attached to the escapement rack to release the carriage automatically from the control of the escapement mechanism at a plurality of predetermined points 40 in the travel of the carriage by moving the rack away from the escapement pinion, comprising a vertical web having a screw-hole centrally located for receiving a screw to attach it to the rack, and a plurality of cams 45 having horizontal upper surfaces to snugly engage the roller-engaging, lower face of the rack and co-operating with the attaching screw to fix the device securely and accurately in place on the rack, and each of the cams constructed to engage the rack-supporting roller and thereby cam the rack away from the escapement pinion in the letter-feed movement of the carriage and to maintain it out of engagement with the roller throughout a carriage-jump of predetermined extent.
5. In a typewriting machine, the combination of a power-driven carriage, a carriage-feeding mechanism including a carriage-rack and a rack-holding pinion, an ordinary carriage-releasing mechanism including a roller operable to raise the feed-rack out of engagement with the pinion to free the carriage, and other carriage-releasing mechanism including a pair of related or connected cams secured to the rack and operable to successively engage with the roller to effect two automatic column-skipping movements of the carriage, with a single letter spacing or typing interval between the skipping movements.
6. In a typewriting machine, the combination of a power-driven carriage, escapement mechanism controlling the letter-feeding of the carriage, comprising an escapement rack on the carriage and a pinion co-operating therewith, and a rack-supporting and lifting roller; a device to cause the carriage to jump forward automatically at a plurality of predetermined points in its travel, said device arranged to be attached to the escapement rack and comprising a vertical web having a screw-hole centrally located for receiving a screw to attach it to the rack, and a plurality of cams extending rearward from the vertical web, said cams having horizontal upper surfaces to snugly engage the roller-engaging, lower face of the rack and co-operating with the attaching screw to fix the device securely and accurately in place on the rack, and each of the cams constructed to engage the rack-supporting roller and thereby cam the rack away from the escapement pinion in the letter-feed movement of the carriage and to maintain it out of engagement with the roller throughout a carriage-jump of predetermined extent.
7. In a typewriting machine, the combination of a power-driven carriage and a platen, typing elements, carriage-feed elements including a rack and a pinion, carriage-releasing means including a roller to separate the rack from the pinion to release the carriage, and a pair of related camming elements secured to and movable with the rack, and each engageable with the carriage-releasing means whereby the carriage will be automatically released to skip a zone of two letter-space distances by the passage of the first cam, receive a single type-impres- 125 sion, and then bring the second cam into 130

operation to automatically skip a second zone of two letter-space distances.

7. In a typewriting machine, the combination of a power-driven carriage, escapement mechanism including a step-by-step escapement-wheel and a pinion, a feed-rack pivoted to the carriage and spring-pressed into operative engagement with the pinion, carriage-releasing mechanism including a roller

arranged to raise the rack out of engagement with the pinion to release the carriage, and a cam-element secured to the rack and arranged to ride over the roller to automatically release and then arrest the carriage for a skipping movement during the normal operation of typing.

ADOLPH G. KUPETZ.
